UNITED STATES PATENT OFFICE.

BERNHARD ENGLE, OF NEW YORK, AND ABRAHAM TWEEL, OF BROOKLYN, NEW YORK.

PENWIPER.

Application filed November 12, 1921. Serial No. 514,547.

To all whom it may concern:

Be it known that we, BERNHARD ENGLE and ABRAHAM TWEEL, citizens of the United States, and residents, respectively, of the 5 borough of Manhattan, city, county, and State of New York, and borough of Brooklyn, county of Kings, city and State of New York, have invented new and useful Improvements in Penwipers, of which the following is the specification.

The device which is the subject of this invention is intended not only as a pen wiper but as a pen cleaner, as it not only removes the ink from the pen but will also clean the 15 pen of any foreign matter and polish the surface cleaned.

An object of the invention is to provide a pen wiping means that is absorbent to a high degree so that the surface presented 20 to the pen in subsequent wipings will be sufficiently dry to take up the ink from the pen. We have however provided a plurality of wiping surfaces which will add materially to the useful life of our device and 25 we have made the absorbent member readily removable so that a new member may be substituted when desired.

These and other objects will be fully set forth in the specification which follows and 30 the accompanying drawing should be referred to for a complete understanding of the specification.

In the drawings:

Fig. 1 shows a side elevation of our device ready for use.

Fig. 2 is a plan view thereof. This view is taken at right angles to the view shown in Figure 1.

Fig. 3 is an end elevation.

Fig. 4 is a side elevation of a modification.

Similar reference numerals indicate like parts in all the figures where they appear.

The device shown in Figure 1, is formed 45 of sheet steel or any other suitable material and should possess a desirable degree of resiliency. In forming this device we produce a loop or return bend portion 5 having the shape and appearance of an open ring or cylinder, the ends of which extend away 50 from the cylindrical member at an angle.

The ends of this metallic member are each shaped as a half of a cylinder, the axis of which is transverse to the axis of the mem-

ber 5. These arms are shown at 6 and 7 in Figure 1 and are provided with lugs as shown at 8, 9, 10, 11, 12, and 13; eight lugs are provided, two at approximately mid-length of each arm and two at the end of each arm, and in each arm we produce a V shaped slit as shown at 14, and it will be noted that the metal freed by this V shaped slit is not removed but is turned inward to 65 produce spurs as shown at 15 and 16 in Figure 1, and as indicated at 17 in Figure 2.

Within the member 5 and the arms 6 and 7 and acting as a lining therefor is a semi-abrasive member 18, which may be leather 70 or any other suitable material, though we prefer that the material employed in this instance should be somewhat if not wholly impervious to ink. This lining member may be cemented within the cylindrical portion 75 5, but will be retained within the arms 6 and 7 by the lugs shown and indicated by the reference characters 9 to 13 inclusive.

Arranged between the arms 6 and 7 and retained by the spurs 15 and 16 is an absorbent member 19, shown as a round plug. This member may be formed of felt and we 80 so prefer it, as felt has sufficient rigidity to prevent crushing or collapsing and to assure sufficiently complete frictional engagement 85 to accomplish the wiping and cleansing of a pen that may be engaged in the manner to be later described.

It will be noted that the outer or free end of the felt member 19 is supported midway between the arms 6 and 7 and this is as we desire it, for when so suspended a pen may be introduced in either of the spaces A or B or between either arm and the 90 felt member.

The wiping is accomplished by introducing the pen into the space A or B and thereafter pressing the arms toward each other. The leather lining of one arm will impinge upon the pen and cause it to engage and 100 to be pressed firmly upon the felt member. The pen is then withdrawn without a release of pressure which will allow the leather to come in contact with the felt member and by this action not only will the ink be removed from the pen but the ink will also be 105 removed from the leather lining, and we have found in continuous operation it is seldom or ever necessary to renew the leather.

To renew the felt member the arms are 110

drawn apart until the spurs 15 and 16 are disengaged from the felt whereupon the felt member may be removed or may be merely given a quarter turn or partial rotation, 5 which will cause the clean portion of the felt to be adjacent to the inner portions of the arms.

In the modification shown in Figure 4 resilient material is used for the arms. In 10 this construction the arms are formed integral and the reduced cylindrical projection 20 may also be formed integral with the arms 21 and 22, the fibrous member 23 is in this construction received and retained 15 in the member 20. The lugs for retaining the leather linings are also omitted, the leather being cemented within the arms 21 and 22. Obviously this device is of cheaper construction. Other modifications may be 20 made within the scope of the appended claims without departing from the principle.

Having carefully and fully described our invention what we claim and desire to secure is—

1. A pen wiper formed of flexible material and comprising an open cylindrical member, arms projecting therefrom, a semi-abrasive

member upon each of said arms and a fibrous member between said arms.

2. A pen wiper having a plurality of arms, a lining member for said arms, a fibrous member retained between said arms, means upon said arms for retaining said lining member and means formed integral with 35 said arms for retaining said fibrous member with its free end normally spaced away from said arms.

3. A pen wiper comprising an open cylindrical member, semi-cylindrical arms formed 40 integral with said open cylindrical member and extending away therefrom, the axis of the cylinder of the arm being transverse to the axis of the first said cylinder, an absorbent member retained between the arms and 45 a semi-abrasive member arranged as a lining for said arms, lugs formed integral with said arms for retaining said lining and a spur formed integral with each said arm, said spurs projecting towards each other and 50 adapted to engage said fibrous member.

Signed at the city, county and State of New York, this 22d of October, 1921.

BERNHARD ENGLE.
ABRAHAM TWEEL.
